A. BLAKE

WASHING MACHINE ATTACHMENT

Filed Sept. 2, 1925

INVENTOR.
A. Blake

ATTORNEY.

Thomas J. Donnelly

UNITED STATES PATENT OFFICE.

ABBIE BLAKE, OF GROSSE POINTE, MICHIGAN.

WASHING-MACHINE ATTACHMENT.

Application filed September 2, 1925. Serial No. 53,990.

My invention relates to a new and useful improvement in a washing machine attachment adapted for mounting on the tub of a washing machine to provide a corrugated 5 surface or a washboard forming portion so that the operator of the washing machine may have always present a washboard forming portion upon which excessively soiled portions of fabrics may be rubbed by hand.

With the conventional washing machines as now constructed, it is necessary for the operator to rub the clothes by hand or to place a wash board in the tub of the washing machine for the rubbing process and remove it therefrom when again using the washing machine tub for operation as a washing machine. Such an arrangement causes a loss of time and requires additional labor. It is also unsatisfactory, inasmuch 10 as the washboard when removed from the tub of the washing machine drips water so as to dampen and wet the floor upon which the washing machine is supported. To overcome these difficulties and to provide a washboard forming portion on the inner surface of the tub of the washing machine which may be present at all times, is one of 15 the objects of the present invention.

Another object of the present invention is 20 the provision of an attachment of this class which may be easily and quickly mounted upon the tub of a washing machine so that it may be used when desired and retained in mounted position for use when desired.

Another object of the invention is the provision of an attachment of this class which may be easily and quickly clamped on the tub of a washing machine and provided with spacing elements adjacent its lower end 25 for extending the lower end outwardly from the upper end to provide a corrugated inclined surface.

Other objects will appear hereinafter.

The invention consists in the combination 30 and arrangement of parts hereinafter described and claimed.

The invention will be best understood from a reference to the accompanying drawings which form a part of this specification, 35 and in which,

Fig. 1 is a vertical sectional view of a washing machine tub showing the invention in side elevation applied thereon,

Fig. 2 is a sectional view taken on substantially line 2--2 of Fig. 1;

Fig. 3 is a sectional view taken on substantially line 3--3 of Fig. 1,

Fig. 4 is a sectional view taken on substantially line 4--4 of Fig. 2,

Fig. 5 is a sectional view similar to Fig. 2 of a modified form of the invention,

Fig. 6 is a fragmentary sectional view taken on substantially line 6--6 of Fig. 5, and

Fig. 7 is a fragmentary sectional view taken on substantially line 7--7 of Fig. 4.

Fig. 8 is a fragmentary view illustrating the soap dish used with the invention.

As shown in the drawings, the invention is adapted for use with a washing machine 70 tub having side walls 11 and a bottom wall 12 supporting a dolly 13. This dolly 13 shown in the drawings may be of any desired type as the particular type of washing machine with which the invention may be used 75 is not important. To afford the corrugated surface I have provided a sheet of metal 12 having its major portion corrugated as shown in the drawings. The lower edge 13 is free from corrugations as is likewise the 80 upper edge. The upper edge is provided with the doubled over portion 14.

A reinforcing, preferably metallic, plate 15 is provided, having its marginal edges doubled over as at 16 and 17 to provide channels or guide ways in which engage the side edges of the member 12. The lower edge of the reinforcing plate 15, as well as the portion 13 of the plate 12, is secured to a wooden 85 spacing block 18 by rivets or any other suitable manner. This block 18 is provided also to prevent rattling of the device from vibrating against the inner surface of the side walls 11 of the tub when the device is used with a washing machine operating under its 90 power. The upper end of the plate 15 is doubled upon itself to provide the doubled over portion 15' which is embraced by the doubled over edge portion 14' of the portion 14. These doubled over portions are 95 such as to snugly engage the side walls 11 of the washing machine tub, it being necessary to slightly spring the doubled over portions downwardly from their main bodies in order to project the wall 11 between the doubled over portions and the main body portions, the material from which the plate 15 and the plate 12 are made being possessed 100 of sufficient resiliency to accomplish this 105 springing effect.

110

Punched out from the doubled over portion 15' are tongues 20 which are spaced apart and which co-operate with similar tongues 19 punched from the doubled over portion 14 to serve as a support for a locking handle 21 which is rockingly mounted on a pin 22 projected through the lugs. This locking handle is provided with an engagement nose 23 which projects through 10 the slot 24 formed in the doubled over portions 14 and 15' as a result of punching tongues therefrom. It is thus seen that both of the doubled over portions 14 and 15' are securely bound together at the upper 15 edge by means of the tongues 19 and 20. In construction, it is desirable that a pair of these locking arms 21 be mounted on the edges.

In the form shown in Fig. 4, the locking 20 arm 21 is in such a position as to securely clamp the members 12 and 15 on the wall 11; in order to release these members from the wall 11, it is necessary to rock the locking member 21 on its pivot 22 so as to move 25 the nose 23 past center, the doubled over portions 14 and 15' being further sprung outwardly from the wall 11 as the nose 23 approaches center. It is evident, therefore, that when the device is locked in the position 30 shown in Fig. 4, the doubled over portions 14 and 15' serve to retain the locking member in operative position and prevent rattling resulting from vibration.

As shown in Fig. 2 and Fig. 5, the spacing 35 bar 25 may be used which is provided with an angularly turned portion 25 adapted for engagement in a slot 18' formed in the block 18. As many of these spacing members 25 may be used as are found necessary or desirable. When the spacing bar 40 is to be inserted in operative position, the lower end of the members 15 and 12 are swung outwardly against the tension of the material from which they are made and the 45 spacing bars inserted in the slots 18'. The resiliency of the metal will then retain the ends of the spacing members 25 in engagement with the inner surface of the wall 11, so that the corrugated or washboard forming 50 portion is at a slight inclination, which is the most desirable position for efficient use.

In Fig. 5 I have shown a modified form 55 in which a corrugated or washboard forming portion 12' is hingedly connected adjacent its upper edge to the U-shaped member 14'' adapted to embrace the wall 11. A reinforcing plate 15'' corresponding to the plate 15 shown in the preferred form is also 60 hingedly connected, as at 29, to the U-shaped member 14'', and a U-shaped reinforcing strip 26 positioned within the U-shaped member 14''. Similar tongues are punched 65 from one side of these U-shaped members for mounting the locking arm 21.

It is evident that with a device of this class a washboard forming member may be easily and quickly mounted on the wall 11 of the tub of the washing machine, so as to accomplish the results desired. The block 70 18 is, of course, quite thin so that the corrugated portion 14 will not lie outwardly from the inner surface of the wall 11 to any great extent. A soap dish 33 is shown mounted on the device by means of a U-shaped bracket 34, which is projected through the members 12 and 15 and angularly turned at its ends.

While I have illustrated and described the preferred form of construction, I do not 80 wish to limit myself to the precise details of structure shown in the drawings, but desire to avail myself of such variations and modifications as come within the scope of the appended claims.

Having thus described my invention, what I claim as new and desire to secure by Letters Patent is:

1. A washing machine attachment of the class described comprising a metallic plate 85 having the major portion of its area corrugated and doubled upon itself adjacent one end; a reinforcing plate for such corrugated plate having its marginal edges at opposite sides angularly turned for embracing the 90 edges of said corrugated plate for reinforcing the same, the upper end of said reinforcing plate being doubled upon itself and lying in engagement with the doubled over portion of said corrugated plate; a pair of 95 spaced tongues struck from each of said doubled over portions; and a locking arm pivotally mounted between said lugs adapted upon movement in one direction for locking 100 said doubled over portions in embracing relation on the wall of the tub of said washing machine.

2. A device of the class described comprising a corrugated plate; a reinforcing plate positioned on one side of said corrugated 105 plate and having opposite edges doubled upon themselves for embracing the edges of said corrugated plate for reinforcing the same, the upper edges of said reinforcing plate and said corrugated plate being 110 doubled upon themselves to provide a substantially U-shaped structure; a pair of spaced tongues punched from the doubled over portion of each of said plates, the corresponding tongues of each plate lying in 115 engagement with each other; a cam locking arm pivotally mounted in said lugs; and a spacing block attached to the lower edges of each of said plates at one side thereof, said spacing block lying in engagement with the 120 surface of said reinforcing plate.

3. A device of the class described comprising a corrugated plate; a reinforcing plate positioned on one side of said corrugated plate and having opposite edges 125

doubled upon themselves for embracing the edges of said corrugated plate for reinforcing the same, the upper edges of said reinforcing plate and said corrugated plate being doubled upon themselves to provide a substantially U-shaped structure; a pair of spaced tongues punched from the doubled over portion of each of said plates, the corresponding tongues of each plate lying in engagement with each other; a cam locking arm pivotally mounted in said lugs; a spacing block attached to the lower edges of each of said plates at one side thereof, said spacing block lying in engagement with the 15 face of said reinforcing plate, said U-shaped structure being adapted for embracing the edge of a washing machine tub, the said spacing block normally engaging against the inner surface of the wall of said tub and 20 provided with slots, and spacing means for engaging in said slots formed in said spacing block for spacing said spacing block from the inner surface of said tub.

4. A device of the class described comprising a corrugated plate; a reinforcing plate positioned on one side of said corrugated plate and having opposite edges doubled upon themselves for embracing the edges of said corrugated plate for reinforcing the same, the upper edges of said rein-

forcing plate and said corrugated plate being doubled upon themselves to provide a substantially U-shaped structure; a pair of spaced tongues punched from the doubled over portion of each of said plates, the corresponding tongues of each plate lying in engagement with each other; a cam locking arm pivotally mounted in said lugs; a spacing block attached to the lower edges of each of said plates at one side thereof, said 35 spacing block lying in engagement with the surface of said reinforcing plate, said U-shaped structure being adapted for embracing the edge of a washing machine tub, the said spacing block normally engaging 40 against the inner surface of the wall of said tub and being provided with slots; spacing means for engaging in said slots formed in said spacing block for spacing said spacing block from the inner surface of said tub; 50 and L-shaped spacing members, the base thereof being adapted for engaging in said slots formed in said spacing block and the legs thereof being adapted for engaging the inner surface of said tub for retaining said 55 plates inclined to the plane of the wall of said tub.

In testimony whereof I have signed the foregoing specification.

ABBIE BLAKE.
